UNITED STATES PATENT OFFICE.

CHARLES HAINES WILLIAMS, OF CHICAGO, ILLINOIS, ASSIGNOR TO CHICAGO RAILWAY EQUIPMENT COMPANY, OF CHICAGO, ILLINOIS, A CORPORATION OF ILLINOIS.

FOURTH-POINT SUPPORT FOR BRAKE-BEAMS.

1,357,369.

Specification of Letters Patent. Patented Nov. 2, 1920.

Application filed June 9, 1919. Serial No. 302,797.

To all whom it may concern:

Be it known that I, CHARLES HAINES WILLIAMS, a citizen of the United States, residing at the city of Chicago, county of Cook, 5 and State of Illinois, have invented a certain new and useful Improvement in Fourth-Point Supports for Brake-Beams, of which the following is a full, clear, and exact description, such as will enable others skilled in the art to which it appertains to make and use the same, reference being had to the accompanying drawings, forming part of this specification, in which—

Figure 1 is a side elevational view of my 15 improved fourth point support for brake beams, and

Fig. 2 is a plan view showing the support as used on either side of the beam.

This invention relates to a new and useful 20 improvement in fourth point supports for brake beams, and is designed particularly to be applied to brake beams in common use, the object being to utilize a single casting for the members constituting the support, and which casting may be applied at 25 either end of the beam, thus making the support reversible. It has been found in practice that inexperienced repair men do not correctly apply the fourth point support 30 to brake beams where they are made for application to the right and left hand sides of the beam. I, therefore, propose to overcome this difficulty by making a single casting which, when assembled with its companion 35 and a wearing surface, permits of the application of the support either on the right or left hand side, as occasion requires.

In the drawings, 1 indicates the spring plank of the truck and 2 the inclined supporting track for the fourth point support. 40 3 is a compression member of a brake beam

and 4 the tension member thereof. 5 is the brake head, which may be of any usual construction, and 6 is the brake hanger.

7 is a casting formed with seats at its 45 extremities to embrace the compression and tension members, these seats being anticlinal, as shown, so that a casting may be applied, top or bottom, at either side of the beam. This casting is provided with a 50 strengthening rib 8 and a hollow boss 9, which latter is designed to receive a fastening means in the form of a bolt 10. The bolt 10 is also employed to secure a rubbing surface on the under face of the lower one 55 of the pair of castings, said rubbing surface being preferably semispherical and being provided with a socket to receive the head of the bolt 10. The semispherical rubbing surface is indicated at 11.

What I claim is:

1. A reversible fourth point support for 60 brake beams in the form of a casting having anticlinal seats for the compression and tension members of the beam located at each 65 end of said casting.

2. A reversible fourth point support for 70 brake beams composed of a pair of like members having oppositely inclined seats at their ends in combination with fastening 75 means for securing said members together.

3. A reversible fourth point support for 75 brake beams comprising like members having anticlinal seats at their opposite ends, fastening means for securing said members together on the beam, and a rubbing surface held in position on one of said members by said fastening means.

In testimony whereof I hereunto affix my signature this 3rd day of June, 1919.

CHARLES HAINES WILLIAMS.
